(57) **CLAIM**

The ornamental design for a watch strap connector, as shown and described.

DESCRIPTION

FIG. 1 is a bottom perspective view of the watch strap connector showing my new design;

FIG. 2 is a bottom view thereof;

FIG. 3 is a top view thereof;

FIG. 4 is a right side view thereof;

FIG. 5 is a left side view thereof;

FIG. 6 is a front view thereof;

FIG. 7 is a rear view thereof; and,

FIG. 8 is top perspective view of the watch strap connector thereof.

The portion(s) of the design shown in broken lines being for the purpose of illustrating environment only and form no part of the claimed design.
